UNITED STATES PATENT OFFICE.

ALFRED OWEN CROZIER, OF NEW YORK, N. Y.

MACHINE FOR MAKING CEMENTITIOUS PRODUCTS.

1,330,172.

Specification of Letters Patent. Patented Feb. 10, 1920.

Application filed June 1, 1918. Serial No. 237,722.

To all whom it may concern:

Be it known that I, ALFRED OWEN CROZIER, a citizen of the United States, temporarily residing at New York, in the county and 5 State of New York, have invented certain new and useful Improvements in Machines for Making Cementitious Products, of which the following is a full, clear, and exact description.

10 This invention relates to the manufacture of concrete brick, building blocks, and other cementitious products, and its object is to provide a reliable and efficient machine for the purpose. Another object is to provide a 15 reliable and efficient machine for use in practising the method or process described in my copending application Ser. No. 224,046, filed March 22nd, 1918. To these and other ends the invention consists in the 20 novel features of construction and combinations of elements hereinafter described.

One embodiment of the invention is illustrated in the accompanying drawings, in which—

25 Figure 1 is a longitudinal section of the complete machine, about on line 1—1 of Fig. 3.

Fig. 2 is a detail side view, partly in longitudinal section, of one end of the link 30 which actuates the toggle provided for raising and lowering the pallet or pallet-table.

Fig. 3 is a plan view.

Fig. 4 is a detail horizontal section about on line 4—4 of Fig. 1.

35 Fig. 5 is a detail section about on line 5—5 of Fig. 3.

Figs. 6, 7 and 8 are detail views showing devices of different lengths provided for varying the throw of the pallet-raising toggle.

40 Fig. 9 is an end view, partly in cross section, from the right of Fig. 1.

Fig. 10 is an end view from the left of Fig. 1.

45 Fig. 10^a is a detail sectional view illustrating a scheme for varying the thickness of the part which is severed from the cementitious column.

Fig. 11 is a plan view of the knives which 50 sever the lower portion of the cementitious column and subdivide the severed portion, showing their co-operation with the lower part of the hollow upright shaft in which the cementitious column is formed.

55 Fig. 12 is a section about on line 12—12 of Fig. 11.

Fig. 13 is a section about on line 13—13 of Fig. 11.

Fig. 14 is a section on line 14—14 of Fig. 11, showing an approved mode of securing the vertical subdividing knives to the horizontal severing knife.

Fig. 15 is a detail sectional plan view of the forward or cutting edges of the vertical knives.

In the apparatus illustrated, an upright 65 hollow shaft 15, Figs. 1 and 9, is provided, into which is deposited the cementitious mixture from which the bricks, blocks or other cementitious products are to be made. Preferably the mixture is of a "slushy" consistency, that is, contains water in excess of the amount required for complete hydration of the cementitious ingredients. In general, it is intended that the products (hereinafter referred to as bricks, but it is to be understood that the invention is not limited to the production of bricks) made from the slushy mixture shall be sufficiently compacted and unwatered to be at least self-sustaining that is, shall not have to be confined or supported 70 in molds, before setting of the mixture begins or has proceeded to any material extent. For this purpose the shaft 15 is filled to a height such that the pressure due to the weight of the superincumbent mass will at 75 least partially compact and unwater the lower portion (from which the bricks are cut) to the extent desired. In practice the compacting and unwatering of the lower portion of the column is carried nearly to 80 the extent required by the pressure mentioned, with the help, if desired, of other agencies which will be explained herein-after.

The lower portion of the solid or non-tubular column (such lower portion being at least partially compacted and unwatered) is severed from the upper portion by means of a horizontal knife 16 which is passed into the shaft, and the severed portion is shaped 100 into the product or products desired. In the machine illustrated the shaping of the severed portion is a dividing of the same into individual bricks, preferably by means of vertical knives 17, Figs. 9, 11, 12 and 13. 105 The lower portion of the column being imprisoned in the rigid lower part of the shaft, distortion of the severed portion is effectually prevented and the knives, or some of them, being of suitable thickness, the 110

knives can enter the column only by compressing the material to a small volume, thus further, and in general completing, the compacting (or densification) and unwatering of the product or products. The removable "pallet" 18, Fig. 1, which forms the bottom of the shaft, is now lowered and removed with the compacted, unwatered and self-sustaining bricks resting upon it, and a fresh pallet is put in place. The knives are now completely withdrawn preferably quickly; thereby allowing the entire column to fall suddenly down upon the pallet. The column is thus subjected to an impact, which has a further densifying and unwatering effect. The steps described are then repeated, fresh concrete of the proper consistency being added to the upper part of the column to maintain the height of the latter.

With the above brief outline in mind the construction and operation of the specific machine illustrated will be readily understood.

25 The lower part 19 of the shaft 15 is preferably in the form of a heavy casting, rectangular in horizontal section, as in Fig. 4, and preferably having the inner surfaces of its front and rear walls substantially vertical. The upper part may be made of sheet metal, and preferably has more or less taper upwardly to facilitate quick descent of the column bodily after the horizontal severing knife 16 is withdrawn. Moreover, the column falls downwardly faster than it spreads laterally, especially in the lower part of the tapered portion, and hence there results a tendency to form spaces or cracks at the walls of the shaft, into which excess water 30 is sucked, thereby aiding the desired unwatering of the mass and expelling such excess water upwardly.

The lower part 19 of shaft 15 is made in two parts or sections, divided horizontally 45 and spaced apart as at 20, Fig. 9, to afford a passageway for the horizontal severing knife 16. The upper section 19^a is supported by means of wings or lugs 21 on frame 22, and the lower section 19^b is 50 rigidly secured on the lugs 23 on the sides of the frame. The front and rear walls of the lower section are provided with vertical slots, as 24, Fig. 11, the intermediate parts of these walls being supported by the necks 55 or webs 25 integral with the outer portions of the walls. The vertical slots constitute passages for the vertical knives 17 which divide and compact laterally the lower portion of the column into bricks, preferably 60 immediately after such portion has been severed from the remainder of the column.

The vertical knives 17 can if desired be secured to the horizontal knife 18 in any convenient manner, as in the dovetail fashion shown in Fig. 14. The knives, both

horizontal and vertical, are solidly attached to the transverse carrier bar 26, which is actuated in harmony with the rest of the machine by means described hereinafter.

As stated above, the severing and dividing knives are made of substantial thickness, so that in forcing their way into the cementitious column they will aid in compacting or densifying the same. The bevel of the knife edge, especially on the upper knife, 70 has an effect which may be important. Thus, by putting the bevel entirely on the underside the densifying effect is all exerted downwardly, upon the portion (of the column) which is imprisoned in the lower 80 section 19^b of the shaft 15. If the bevel is all on the upper side of the knife, the densifying effect is all exerted on the unsevered part of the column, while if the bevel is equal on the two sides the densifying effect 85 is divided equally, and by putting more of the bevel on one side than on the other, the effect will be divided correspondingly. For instance, with the knife edge shown in Fig. 13 greater densifying effect will be exerted 90 on the part (of the column) above the plane of the knife-passage 20, Fig. 9, than on the portion below it. On the vertical knives the bevels may be as shown in Fig. 15, and the knives may be made successively longer 95 from the outer knives inwardly. In such case the tendency is to crowd the cementitious material laterally, to compensate for the omission of knives at the outer sides or faces of the outermost bricks.

100 Along its side edges the horizontal knife 16, Figs. 1, 4 and 9, is provided with guide sleeves 27 fitted to slide on parallel longitudinal guide rails 28 firmly secured to the adjacent side members of the frame 22. The carrier bar 26 is reciprocated longitudinally of the machine by means of two connecting rods 29 (see also Fig. 3) connected at their rear ends to crank pins on the gears 30. The latter are driven by pinions 31, 110 Fig. 10, on the ends of the transverse shaft 32, which is rotated by gear 33 meshing with a pinion 34 on the main driving shaft 35. The latter shaft is itself driven by a pulley 36. The pinion 34 is loose on its shaft, but 115 is connected thereto at proper intervals, as will be explained hereinafter, by a clutch 37 of any suitable character, actuated by a cam 38 on shaft 32 through the medium of rod 39 (Fig. 1) and arm 40.

120 The pallets 18 for use under the cementitious column are arranged in a stack 41, Fig. 1, from the bottom of which they are fed out, one at a time, and carried to the shaft 15. For this purpose a horizontally reciprocating pallet-shifter is provided, in the form of an open frame 42 (see also Fig. 3) which is actuated by links 43 connected to rocker arms 44 on the transverse rock shaft 44^a (Fig. 1) rocked by a cam 45 on shaft 46, 130

through the medium of link 47 coöperating with said cam. Link 47 slides in guides 48 and is connected to one of the arms 44 by a second link 49. On the inside of the side members of the frame 42 are four pairs of weighted dogs 50, held by gravity against stops 51 which serve to limit their counter-clockwise movement. The two pallets shown at 18^a, 18^b, Fig. 1, rest at their ends on side rails 52, Figs. 3 and 5, and in front of lugs 53 which serve as stops to prevent rearward displacement or movement of the pallets when the dogs are retracted with the frame 42. When the frame is advanced (toward the right in Fig. 1), the brick laden pallet 18, the ends of which overhang the table 54, is pushed along on its rails 55 to the position shown in dotted lines, pallet 18^a is moved over upon the table, pallet 18^b is shifted to the position just vacated by pallet 18^a, and the rear pair of dogs push another pallet from the bottom of the stack and move it to the position of pallet 18^a. When the frame or pallet shifter is retracted the dogs pass idly under the pallets to the initial position shown in Fig. 1.

The table 54, Fig. 1, is fixed on top of two vertical slides 56 working between guide rollers 57 and actuated by a toggle composed of members 58^a, 58^b. The latter members are mounted on a transverse shaft 59 and are rocked at proper intervals (as will be described hereinafter) by a link 60, Figs. 1 and 3, connected at its rear to a slide 61 which is reciprocated in guides 62 by a cam 63 on the end of shaft 46. When the toggle is straight it bears against the transverse frame-member 64, but the link 60 has a yielding connection (see Fig. 2) so that it can advance a little farther without injury to the parts, thus obviating the necessity of accurate adjustment, etc. The wrist pin 65, Fig. 2, by which the link 60 is connected to the arm 59^a (Fig. 3) on the end of shaft 45 to rock the latter, is seated in a recess in the link and is held therein by the slide 66 which can be withdrawn by means of the handle 67, thereby permitting link 60 to be lifted off said pin.

Shaft 46, which it will be remembered, carries cams 45 and 63 which actuate the pallet-shifter 42 and table 54, is rotated by a worm gear 68, Fig. 1, worm 69, vertical shaft 70, and bevel pinion 71 meshing with bevel pinion 72 on driving shaft 35.

The operation of the machine will now be readily understood. The parts being in the positions shown in Fig. 1, the pallet-shifter 42 is advanced (toward the right) carrying the brick laden pallet 18 to the dotted-line position and placing pallet 18^b upon the table 54. The latter is now raised (by straightening of the toggle 58^a—58^b), bringing the fresh pallet firmly against the bottom of the lower shaft-section 19^b. Knife

16 is now fully retracted, from the cementitious column, by the connecting rods 29, whereupon the column drops in the shaft 15 with a heavy jolt upon the pallet, and fills the said lower shaft-section. Knife 16 is now advanced into the passage between the two shaft sections 19^a, 19^b, and on through the column thus severing the lower portion of the column, in said shaft-section 19^b. Continuing, the vertical knives 17 enter the vertical slots in section 19^b and divide the severed portion of the column into individual bricks, after which the vertical knives are retracted, and the table 54 lowered, to the positions shown in Fig. 1. In the meantime the filled pallet (shown in dotted lines) has been removed and the pallet-shifter retracted, thus completing the cycle of the machine.

Instead of providing several slots, one above the other, in the shaft to permit portions of different heights to be severed from the column, I employ a method which is more flexible, so to speak, in that it permits smaller variations of height to be made. For this purpose the vertical supports 73, Figs. 1 and 3, which carry the guide rollers 57 and the supporting roller 74 for the pallet-shifter 42, and the vertical supports 75, Figs. 1 and 5, which carry the pallet rails 52 and the roller 76, are capable of vertical adjustment on the frame of the machine. The throw of the toggle is also varied by inserting in the upper member 58^a spacing members of different lengths, such as shown at 77, 78, 79, Figs. 6, 7 and 8 (see also Fig. 9), and by shifting the wrist-pin 65, Fig. 1, in the slot 80 in arm 59^a, which rocks the shaft 59 and the lower toggle members 58^b. The hollow shaft 15 is lengthened downwardly by removing the lower section 19^b and substituting another of the proper depth, the additional depth being obtained by extending the section below the plane of the supporting lugs 23, Fig. 9; or, preferably, an additional portion of proper thickness, as for example the part 19^c, Fig. 10^a, is secured on the underside of the section 19^b. Another horizontal severing knife, without vertical knives, is also substituted for the one shown; or, if the block severed from the column is to be divided into smaller blocks, a horizontal knife with the proper number of vertical knives of suitable height.

It is to be understood that the invention is not limited to the specific construction herein illustrated and described, but can be embodied in other forms without departure from its spirit as defined by the following claims:

I claim:

1. In a machine for the manufacture of cementitious products, in combination, a hollow shaft or container for an unset cem-

- entitious column, a removable closure for the bottom of the shaft, a horizontal knife of substantial thickness movable into the lower portion of the shaft to sever from the cementitious column the part thereof below the knife and exert a compacting or densifying effect on the lower portion of the column, mechanism for advancing and retracting the knife, means for removing said bottom closure and placing another in position, and means for actuating said means and mechanism in proper order.
2. In a machine for the manufacture of cementitious products, in combination, a hollow shaft or container for an unset cementitious column, a knife movable into and out of the column to sever a portion therefrom while such portion is imprisoned whereby distortion of the same is prevented, means for actuating the knife, and means for removing the severed portion of the column.
3. In a machine for the manufacture of cementitious products, in combination, a hollow shaft or container for an unset cementitious column, a horizontal knife movable into and out of the column to sever a portion therefrom while the same is imprisoned, one or more vertical knives arranged to divide the said portion of the column into parts after said portion is severed from the column while it is imprisoned, whereby distortion of the said portion and its parts is prevented, and means for actuating the horizontal and vertical knives.
4. In a machine for the manufacture of cementitious products, in combination, an upright hollow shaft or container for an unset cementitious column, a horizontal knife of substantial thickness movable into and out of the lower portion of the column to exert a compacting or densifying effect upon said lower portion and to sever from the column the part below the knife, one or more vertical knives movable into and out of the column to divide the portion thereof below the horizontal knife, and means for actuating the knives.
5. In a machine for the manufacture of cementitious products, in combination, an upright, hollow shaft or container for an unset cementitious column, means for severing a portion of the column from one end thereof while such end is still imprisoned, means for dividing such portion into parts, and means for removing said parts.
6. In a machine for the manufacture of cementitious products, in combination, an upright hollow shaft or container for an unset cementitious column, a horizontal knife movable into and out of the column to sever a portion thereof, one or more vertical knives connected to the horizontal knife beneath the same and arranged to enter the column in rear of the cutting edge of the horizontal knife to divide the severed portion of the column into parts after such portion has been severed, and means for actuating the knives.
7. In a machine for the manufacture of cementitious products, in combination, a hollow shaft or container for an unset cementitious column; means for severing and dividing a portion of the column while such portion is still imprisoned to prevent distortion thereof, comprising a knife movable into the column transversely thereof and one or more knives attached to the horizontal knife on one side of the same; and mechanism for actuating said means.
8. In a machine for the manufacture of cementitious products, in combination, an upright hollow shaft or container for an unset cementitious column, a transverse carrier bar adjacent to the shaft and movable toward and from the same, a horizontal knife connected to said bar for actuation thereby and movable into and out of the shaft to sever a portion of the cementitious column therein, one or more vertical knives connected to the said bar and horizontal knife and movable into and out of the shaft to divide the said portion in one or more vertical planes, and means for actuating the carrier bar.
9. In a machine for the manufacture of cementitious products, in combination, an upright hollow shaft for an unset cementitious column, means for severing a portion of the column from the lower part thereof, and means permitting lengthening the part of the shaft below the path of the severing means, whereby portions of different heights may be severed from the column.
10. In a machine for the manufacture of cementitious products, in combination, an upright hollow shaft or container for an unset cementitious column, said shaft having a lower part permitting variation of the height of the lower part of the shaft, a removable bottom for said lower part; a vertically adjustable support for the removable bottom; and means movable into and out of the shaft between the lower part and the upper part to sever a portion of the column therein.
11. In a machine for the manufacture of cementitious products, in combination, an upright hollow shaft or container for an unset cementitious column, said shaft having a lower part; means movable into and out of the shaft between said lower part and the upper part to sever a portion of the column therein; a removable bottom for the lower part of the shaft; vertically movable and vertically adjustable supporting means for said removable bottom; and horizontally movable and vertically adjustable means for

displacing the removable bottom from said supporting means and for putting another removable bottom in position thereon.

12. In a machine for the manufacture of 5 cementitious products, in combination, a hollow shaft or container for an unset cementitious column, a knife movable into and out of the shaft to sever successive sections of the column while still imprisoned in the 10 shaft from one end thereof, means for operating upon such severed sections to shape the same into the desired products, and mechanism for actuating said knife and said shaping means in proper order.

15 13. In a machine for the manufacture of cementitious products, in combination, an upright hollow shaft or container for an

unset cementitious column, a removable closure for the bottom of the shaft, a horizontal knife movable into and out of the 20 shaft to sever from the column the portion thereof between the knife and said closure, means for shaping said portion of the column, mechanism for removing said closure with the shaped portion of the column 25 thereon and positioning another closure thereunder, and power-driven means for actuating the knife, shaping means, and closure removing and positioning means in proper order.

In testimony whereof I hereunto affix my signature.

ALFRED OWEN CROZIER.
